CEMENT BAILER

Walter Creek, Wichita, Kans., assignor of one-third to Viola E. Creek, Wichita, Kans., and one-third to Harold C. Creek, Eureka, Kans.

Application April 13, 1934, Serial No. 720,390

6 Claims. (Cl. 166—19)

My invention relates to an improvement in cementing bailers for use in cementing tubing in oil wells. The object of my invention is to provide a device such that concrete may be placed at a definite place in an oil well. Another object is to provide a device that will take the concrete to the desired place in the oil well and deposit it there without the water and oil in the well being allowed to mix with the concrete before it reaches the place where it is to be deposited. These and other objects will be more fully described as this description progresses.

Now referring to the drawings in which the same characters of reference designate the same part throughout the several figures, Fig. 1 is a sectional view of my concrete carrying device. Fig. 2 is a side view of my concrete carrying device. Fig. 3 is a front view of my concrete carrying device. Fig. 4 is a sectional view taken on the line IV—IV in Fig. 3. Fig. 5 is a side view partly in section of my concrete carrying device in the dumping position. Fig. 6 is a side view partly in section taken at right angles to that shown in Fig. 5. Fig. 7 is a sectional view taken on the line VII—VII in Fig. 3. Fig. 8 is a plan view of the polished rod slip. Fig. 9 is a side view of the polished rod slip. Fig. 10 is an enlarged detail sectional view of the hydraulic release valve and adjacent parts. Fig. 11 is a sectional view taken on the line XI—XI in Fig. 10. Fig. 12 is a sectional view taken on the line XII—XII in Fig. 10. Fig. 13 is a longitudinal sectional view similar to Fig. 10 but with some of the parts shown in elevation instead of in section.

In the drawings is shown a tubular element 10 having a closed upper end which is provided with an eye 11 by which the device may be supported. At 12 is a casting, into which the lower end of the tubular element 10 is threaded. At 13 is a second tubular element, the lower end of which is open and the upper end of which is threaded onto the casting 12. At 14 is an opening in the tube 13, the object of which will be later explained. At 15 is another opening in the tubular element 13, through which the tubular element 13 may be filled with concrete as will be later explained. At 16 is a polished piston rod, which passes through the casting 12 in which is a packing gland 17 around the piston rod 16, said packing gland being held in place and under compression by the packing nut 18 which is threaded into the casting 12.

On the upper end of the piston rod and rigidly attached thereto is a piston 19 which fits in the tubular element 10 as a cylinder. Between the upper end of the tubular element 10 and the pis-

ton 19 and under pressure therebetween is a helical spring 20 exerting its pressure in a downward direction on the piston 19. In the tubular element 13 is a spider element 21 having a hole therein through which the lower end of the piston rod 16 may slide, the spider acting as a guide for the lower end of the piston rod.

Rigidly affixed to the polished piston rod 16 is a collar 22 on which rests a helical spring 23 that is positioned around the polished piston rod 16. At 24 is a polished rod slip which rests on the spring 23 and is slidably mounted on the polished piston rod 16. At 25 is a second collar which is rigidly positioned on the polished piston rod 16. The collar 25 is so positioned on the polished piston rod that the polished rod slip 24 rests against the collar 25 which serves to hold the polished rod slip 24 and the spring 23 in their proper position.

On the opposite sides of the polished rod slip 24 is pivotally mounted a pair of releasing dogs 25, said dogs 26 are mounted between outwardly projecting ears 27 on the polished rod slip 24. At 28 is a pair of outwardly projecting ears on the polished rod slip and through which is a pin 24a, the object of which will be later explained.

In the tubular element 13 is a pair of slots 29 positioned on opposite sides of the tubular element 13. The sharp upper ends of the releasing dogs 26 project through the slots 29 and slide against the oil well tubing 30 as the device is lowered into the oil well. On each side of both of the slots 29 and extending inwardly from the wall of the tubular element 13 is a pair of ear like elements 31 which function as guides for the releasing dogs 26 to slide between.

In the casting 12 is a hole in which a tubular element 32 is placed and is rigidly maintained in place by the threads 33 on the tube 32 which are screwed into threads in the hole in the casting 12. The lower end of the tubular element 32 is provided with a hexagon shaped portion 32' on which a wrench may be placed for the purpose of turning the tubular element 32. In the upper end of the tubular element 32 is a port 34 which is in registry with a port hole 35 that connects between the port 34 and the interior space in the tubular element 10.

At 36 is a cap element resting on top of the tubular element 32 and serving as a closure for said tube. Rigidly attached to said cap 36 is a U shaped element 37 to which is attached one end of a helical spring 38.

Snugly fitted within the tube 32 is a second tube 39 which is adapted to be slipped up and down in the tube 32 and thereby function to open and

close the port 34. It will be understood that the upper end of the tube 39 is open and the helical spring 38 is positioned in the tube 39. At the bottom end of the tube 39 is a pin 40 which passes through the walls of the tube 39 and to which is attached the lower end of the helical spring 38, said spring 38 functioning to pull the tube 39 up in the tube 32 so that the wall of the tube 39 will pass the port 34 and close the port. At 41 is a clevis that is swung on the pin 40 and attached to the clevis 41 is a cable 42 on the lower end of which is a hook 43 that is adapted to be hooked on the pin 24a in the polished rod slip 24 so that the downward movement of the polished rod slip 24 will impart the same downward movement of the tubular element 39 and thereby open the port 34.

At 44 is a horizontal hole into which opens a vertical hole 45 in the casting 12, said hole 45 opens into the space in the tubular element 10. In the hole 44 is threaded a valve seat 46 in which is seated a ball 47 which is compressed between the ball 47 and the wall at the rear of the hole 44. At 49, in Fig. 10, is shown a threaded hose fitting or a pipe that is threaded into the hole 44 through which oil may be pumped to the space in the tubular element 10 for purposes as will be later explained.

After the oil has been pumped into the tubular element it will be retained there by the ball valve 47 and the fitting 49 may be removed after which a plug 50, see Fig. 13, may be screwed in the hole 44 to close the hole.

It will be understood that the tubular element 13 is long, probably thirty feet or more in length, and at the bottom of which is a closure element 51, a portion of which is adapted to be received inside the tubular element 13, there being a flange portion 52 which rests against the lower end of the tubular element 13 and serves as a tight closure for the open end of the tubular element 13. On the bottom of the closure element 51 is rigidly attached a flexible circular element 53 such as a piece of belting or stiff leather which is large enough to fit in the oil well tubing 30 and act as a guide for the element 13, also to act as a feeler to tell when the device contacts water or oil in the tubing 30. At 54 is a rod or cable, the upper end of which is attached to the lower end of the polished rod. The lower end of the rod or cable 54 is attached to an eye 55 that is rigidly affixed to the element 51. Attention is called to the fact that the eye 55 is located off of the center of the element 51 so that when the element 51 is dropped from the tubular element 13, it will turn edge ways as shown in Fig. 5.

Now the operation of my apparatus is as follows:

The apparatus for carrying the concrete or cement is prepared for use by first unhooking the hook 43 from the pin 24a, whereupon the spring 38 pulls the tube 39 upwardly in the tube 32 so that the upper end of the tube 39 passes the port 34 and thereby closes the port as shown in Fig. 10. Now the plug 50 is removed from the hole 44 and a hose connection or a pipe 49 is screwed in the hole 44 whereupon a liquid, preferably oil, is pumped through the valve 46—47 into the tubular element 10 and under the piston 19 thereby raising the piston and its connected parts against the pressure of the spring 20. The oil is pumped into the tubular element 10 until the piston is raised to such a point that the closure element 51 has been pulled into its closed position against the end of the tubular element 13 as shown in

Fig. 1. Now the hose connection or pipe 49 is removed from the hole 44 and the plug 50 is replaced therein.

Now the well is prepared to receive the concrete or cement by raising the tubing 30 in the well and removing a joint of the tubing. Then the apparatus for carrying the cement is suspended in the oil derrick over the well and lowered therein to a point where the opening 15 in the tubular element 13 is at a convenient position for the workmen who then fill the tubular element 13 with concrete or cement by passing the concrete or cement through the opening 15 and dropping it in the tubular element 13.

After the tubular element 13 has been filled with the concrete or cement, the apparatus is lowered in the well. On the way down, the sharp points on the upper end of the releasing dogs 26 slide against the wall of the oil well tubing 30 as illustrated in Fig. 3. When the apparatus has reached the place where it is desired to dump the concrete or cement, the apparatus is slowly raised. The sharp points of the releasing dogs 26 catch on the wall of the oil well tubing 30 and hold the polished rod slip 24 stationary, while the balance of the apparatus continues to move upwardly thereby slipping the polished piston rod upwardly through the slip 24, thereby compressing the spring 23 and holding the tube 39 stationary, which results in the removal of the tube 39 from in front of the port 34 so the port is open, at which time the spring 20 pushes the piston 19 downward, discharging the oil thereunder through the hole 35, port 34 and through the tube 39 where it is discharged into the oil well. Simultaneously with this action just described the piston rod 16 is forced downwardly, the collar 25 contacts the slip 24 and pushes it downwardly, thereby dragging the points of the releasing dogs 26 inside the tube like element 13 as shown in Fig. 6. Simultaneously with this action, another action takes place which is as follows. The piston rod 16 being moved downwardly, the sealing element 51 was allowed to drop from its place at the end of the tubular element 13 at which time it took the position shown in Fig. 5, and the concrete or cement in the tubular element 13 was discharged, by gravity, from the tubular element 13 into the oil well as illustrated in Fig. 17. Now the apparatus is removed from the oil well. If more concrete or cement is desired in the well than the apparatus would carry at one time; the oil well tubing is again raised, another joint of the oil well tubing is removed and the process of recharging the apparatus with concrete or cement and placing it in the oil well is repeated, the same as above described.

Now having fully described my invention, what I claim as new and desire to secure by Letters Patent is:

1. An apparatus for cementing oil well tubing comprising, means for supporting said apparatus, a container for holding cement, a removable bottom for said container, a hydraulic means for retaining said bottom on said container, and means for effecting the release and removal of said bottom from said container upon the upward movement of said container in the oil well tubing.

2. An apparatus for cementing oil well tubing comprising, means for supporting said apparatus, an open ended container for holding cement, a removable bottom for said container, hydraulic means for retaining said bottom on said container and releasing it therefrom, said hydraulic means comprising a cylinder, a piston in said cylinder, a piston rod attached to said piston, a cylinder

head beneath said piston, said piston rod slidably passing through said head, an element connecting between the lower end of said piston and said bottom, means for applying hydraulic pressure between said piston and said head for the purpose of retaining said bottom on said container.

3. An apparatus for cementing oil well tubing as described in claim 2, valve means for releasing said hydraulic pressure, said valve means being operable by a mechanism on said piston rod, said mechanism comprising a slip element on said piston rod, dogs pivotally mounted on said slip, said dogs having sharp upwardly directed points which protrude through slots in the container element and rest against the oil well tubing, a spring carried on said piston rod and supporting said slip, means connecting between said slip and said valve means for releasing said hydraulic pressure, said dogs being adapted to catch on the oil well tubing and hold the slip element stationary upon the upward movement of said apparatus and thereby effect the opening of said

valve for the release of said hydraulic pressure as and for the purpose set forth.

4. An apparatus for cementing oil well tubing as described in claim 2, a spring in said cylinder, said spring being under compression between said piston and the upper end of said cylinder and functioning to move the piston downward to release the bottom from said container upon the release of the hydraulic pressure.

5. An apparatus for cementing oil well tubing as described in claim 2, an opening in the upper portion of said container for the purpose of loading the container.

6. An apparatus for cementing oil well tubing as described in claim 2, valve means for retaining or releasing a hydraulic pressure between said piston and cylinder head, means on said piston rod for opening said valve, a connecting element between said valve and means for opening said valve and means for disconnecting said connecting element from said means for opening said valve.

WALTER CREEK.
